UNITED STATES PATENT OFFICE

140,282

DESIGN FOR A BRACELET OR SIMILAR ARTICLE

Simon Fischer, Brooklyn, N. Y.

Application November 16, 1944, Serial No. 116,354

Term of patent 7 years

(Cl. D45—4).

To all whom it may concern:

Be it known that Simon Fischer, a citizen of the United States and resident of the Borough of Brooklyn, in the county of Kings and State of New York, has invented a new, original, and ornamental Design for a Bracelet or Similar Article, of which the following is a specification, reference being had to the accompanying drawing, forming part thereof, in which

Fig. 1 is a top plan view of a bracelet embodying my new design with the ends thereof separated and the bracelet lying flat;

Fig. 2 is a front edge view of the bracelet; and Fig. 3 is an end edge view thereof.

The dot-and-dash line illustration is a continuation of the portion shown in full lines terminating in a conventional bracelet fastener.

I claim:

The ornamental design for a bracelet or similar article, substantially as shown and described.

SIMON FISCHER.
